FIG. 1.

C. MALITCH.

RAIL CHAIR.

APPLICATION FILED APR. 18, 1922.

1,428,534.

Patented July 25, 1922.

2 SHEETS—SHEET 2.

UNITED STATES PATENT OFFICE.

CHARLES MALITCH, OF HAMILTON, OHIO.

RAIL CHAIR.

1,423,534.

Specification of Letters Patent. Patented July 25, 1922.

Application filed April 18, 1922. Serial No. 554,641.

To all whom it may concern:

Be it known that I, CHARLES MALITCH, a citizen of the United States, residing at Hamilton, in the county of Butler and State 5 of Ohio, have invented certain new and useful Improvements in Rail Chairs, of which the following is a specification.

My present invention, which generally relates to improvements in that type of rail 10 chair and joint structures disclosed in my Patents No. 1,390,919, dated September 13, 1921 and No. 1,411,738, dated April 4, 1922, primarily has for its purpose to provide a new and improved rail chair, of the general 15 type stated, of a relatively simple construction, in which the direct connection of the rail ends and the chair is a boltless one and in which provision is also made for a more convenient and positive interlocking engagement 20 of the rail ends and their coengaging chair parts, and in such manner that the assemblage of the chair and the rails is facilitated when the chair parts are to be secured upon the rail tie.

25 In my Patent No. 1,411,738, before mentioned, the chair structure includes iron and wooden wedges and wooden filler members that are adapted for being inserted, in the direction of their length, at each side of the 30 rail web and between the said web and the vertical flanges of the opposite or two-part rail chair sections.

My present invention does away with the use of wooden wedges or filler members, 35 since all the parts thereof are of metal. The present invention includes an improved design of a single malleable iron wedge, that is not adapted to be driven into operative position by forcing it endwise into place, as in 40 the patented construction mentioned but is adapted for being driven, in vertical direction along the full length thereof, between the vertical chair flange at one side of the rail and a filler member held against the adjacent side of the rail web, the filler and 45 wedge members being also provided with means interlockably connecting them to hold the wedge from working loose in horizontal direction.

50 Another object of my present invention is to provide a combination of rail chair parts, for engaging the ends of adjacent rail sections, in which is included a single wedge member that is designed for being engaged by and held from working loose in vertical

direction by the impact of the flanges of the passing wheel which tend to constantly hold the said single wedge to its downward or wedging position and secured against loosening upwardly under the jars and hammering action incident in the use of rail chairs of the general type referred to.

In the construction disclosed in my patent aforesaid, the rail ends receiving seat or chair body is held down by spikes whose 65 heads directly engage the opposite base flanges of the chair or seat body proper.

In my present construction, provision is made, by reason of special formation of the said base flanges of the chair, whereby the 70 spikes, when driven home, are caused to engage the opposite flanges of the rail base to thereby effectively hold down the rail end under the varying condition of expansion and contraction of the parts and in a more 75 positive clamping engagement with the chair or seat base than is possible where the spikes engage the chair flanges, as in my patented construction mentioned.

With the above and other minor objects in 80 view and which will hereinafter be incidentally mentioned, my present invention comprehends an improved rail chair which embodies the peculiar features of construction and novel arrangement of the parts 85 fully mentioned in the following detailed description, specifically stated in the appended claims and illustrated in the accompanying drawings, in which:

Figure 1 is a perspective view of a pre- 90 fered form of my new and improved rail chair.

Figure 2 is a horizontal section thereof, taken substantially on the line 2—2 of Figure 95 3.

Figure 3 is a transverse section of the same on the line 3—3 of Figure 2.

Figure 4 is a perspective view of the member which constitutes the filler for the space at one side of the rail web.

Figure 5 is a perspective view of the single wedge member used in my present and preferable construction of rail chair.

Figure 6 is a transverse section of my improved construction of rail chair, taken 105 substantially on the line 6—6 on Figure 7, and illustrating the manner in which the chair, the filler, the wedge member and the rail ends may be held together with the ordinary standard bolts.

Figure 7 is a horizontal section thereof taken substantially on the line 7—7 on Figure 6, the bolts being omitted.

Figure 8 is a perspective view of the form 5 of wedge used in the modified construction of my invention illustrated in Figures 6 and 7.

In my present invention, the rail chair or 10 seat is a single casting, preferably 10" long, and which, when operatively applied, may, as in my patented chair structure mentioned, fit down in a recess 7^a in the top of the cross tie 7 or be secured directly on top of the 15 said tie, as best shown in Figure 6, by a pair of spaced spikes 5—5 at one side and a midway-positioned spike 5^a at the opposite side, the said spikes, in my present invention, when driven home, engaging the opposite flanges of the rail base, as will herein- 20 after be further explained.

In the preferred construction of my present improvements, and as best illustrated in Figures 1, 2 and 3 of the drawings, the rail chair is a single casting 2, the opposite sides 25 of which each terminate in an upwardly extending vertical flange, one of such flanges, in the present construction, constituting a shoe or filler 2^a for directly engaging one side of the webs of the adjacent rail ends 30 and against which the said rail webs are laterally clamped in the manner presently explained.

By referring to Figures 2 and 3, it will be noticed the shoe or filler 2^a, before mentioned, and which is an integral part of the chair body or casting, is the full length of the chair body and of a thickness to fill the space between the adjacent faces of the webs of the rail ends and the outer vertical 40 plane of the rail heads, as is clearly shown in Figure 3.

3 designates a filler member or plate and it is of a thickness similar to the chair shoe 2^a and it engages the opposite faces of the 45 rail webs and the said member 3 has a series of horizontally arranged serrations 30 on the faces thereof, the purpose of which will presently be explained.

By referring to Figures 2 and 3, it will 50 be observed in my present construction of rail chair, the vertical flange 2^b of the chair body is spaced a sufficient distance from the rails to position its vertical face far enough away from the corresponding faces of the 55 rail webs to provide for a proper and convenient fitting of the filler 3 and a wedge member 4 which, in the practical development of my invention, is a steel bar or plate the full length of the chair body, and is 60 slightly tapering from the top to the bottom in cross section.

The inner face of the wedge member 4 has a series of ratchet-like serrations 40 and these are adapted for interlocking with the 65 like serrations 30 on the filler member 3,

before referred to, and other serrations 41 to engage serrations 2^a on the member 2^b, as the said wedge 4 is driven down, its full length, between the flange 2^b and the filler 3, it being understood that as the wedge 4 70 is driven down, as stated, the coengaging parts mentioned will be held in a tightly clamped relation. The filler 3 is held from endwise displacement by the provision of lateral studs 31, cast with the filler, which fit into the apertures 60 in the rail web, the latter being of the usual shape to allow for the normal expansion and contraction of the rails without effecting the connection between the said rails and the said filler 80 member 3.

To hold the wedge 4 against working endwise, that is, in horizontal direction, the outer face of the said wedge has one or more vertical ribs 42 adapted for engaging vertical grooves 26 in the adjacent face of the chair flange 2^b and the inner face of the said wedge 4 is formed with a series of vertical grooves 47 for engaging correspondingly shaped ribs 37 on the filler 3, as shown. 90

By referring more particularly to Figure 2 of the drawings, it will be seen that one of the opposite horizontal flanges of the chair 2 has a pair of spaced semi-circular edge notches 22 and the opposite chair flange has 95 a single semi-circular notch 22 and the several mentioned notches extend inwardly sufficiently to expose the opposite outer edges of the rail base flanges to provide for readily driving the spikes down with their heads 100 clamping against the said rail flanges, as is clearly shown in Figure 3 of the drawings.

In my present construction of rail chair or joint, the single wedge member 4, before mentioned, has its upper edge crowned from 105 its opposite ends to its center. In other words, the said top surface or edge of the wedge inclines downwardly from the crown or high point 44, which point, when the wedge is driven home and interlocked with the filler member 3 and the adjacent flange 2^b of the chair, as before stated, is positioned low enough to permit the flanges of the truck wheels to clear the said high point 44 of the wedge but should, for any reason, 115 the wedge 4 loosen or work upwardly, the said high or crown portion 44 will come within the path of movement of the wheel flanges which, as they engage the crown edge of the said wedge 4, will force such wedge downwardly back into interlocked engagement with the filler 3 and flange 2^b. 120

In Figures 6, 7 and 8, is shown a slightly modified arrangement of my present invention, and in such showing instead of providing the filler 3 with studs 31 for interlocking with the rail webs, as stated, the said filler 3 at one side of the rail and the shoe 2^a at the opposite side of the rail, as also the chair flange 2^b, are provided with 125 130

suitable apertures 33-43 and 23 respectively, the said apertures being relatively arranged so that when the several parts mentioned are operatively assembled the said 5 apertures will register with the apertures 60 in the rail webs and when the parts are thus assembled the usual standard bolts 9 may be utilized for clamping the several parts mentioned together in transverse relation, as will be readily understood from 10 Figure 6 of the drawings.

When used in connection with the standard bolts 9, as in Figures 6, 7 and 8, the wedge member is preferably formed with 15 slotways 43-43 that extend upwardly from the lower edge thereof and which are so disposed along the wedge that when the parts are assembled with the wedge down between the filler 3 and the adjacent chair 20 flange the said wedge member will be held from working loose in the horizontal direction by the bolts 9.

From the foregoing, taken in connection with the accompanying drawings, the complete construction, the manner in which the chair parts are assembled for use in connection with or disconnected from the rail ends, as may be necessary, will be readily understood by those familiar with railway 30 track construction.

What I claim is:

1. A combined rail chair and joint comprising a chair including a base adapted for being secured upon a rail tie, the said base 35 having a seat, a pair of opposing rail ends whose base portions are received on the chair seat, the said chair having at each side a vertically extended longitudinal flange, one of the said flanges opposing the adjacent 40 web faces at one side of the rail ends, a filler member at the other side of the webs of the rail ends, the said filler opposing its respective adjacent vertical chair flange, a wedge interposed between the said filler and the adjacent rail chair flange, and means for 45 clamping the several parts in interlocked engagement, the said wedge member having its upper edge crowned from the ends toward the center whereby to present a top 50 surface on the wedge adapted for being engaged by the flanges of passing car wheels when the said wedge works upwardly to bring the said upper edge in a plane of travel of the flanges of the car wheel.

2. A combined rail chair and joint comprising a chair that includes a base adapted for being secured upon a rail tie, which base has a seat, a pair of opposing rail ends whose base portions are received upon the 55 chair seat, the said chair having at each side a vertically extended longitudinal flange, one of the said flanges opposing the

web faces at one side of the rail ends, a filler member that engages the faces at the other side of the webs of the rail ends, the 65 said filler opposing its respective adjacent vertical chair flange, a wedge interposed between the said filler and the adjacent rail chair flange, and means for clamping the several parts in interlocked engagement, 70 said means including clamp bolts that pass through the rail ends, the vertical flanges of the chair and the filler, the aforesaid wedge member having vertical slotways in its lower edge for fitting over the aforesaid 75 bolts when the aforesaid parts are operatively assembled.

3. A combined rail chair and joint comprising in combination with the adjacent ends of two rail sections; a chair including 80 a rail tie engaging base having a seat for receiving and embracing the base flanges of the adjacent rail ends, the said chair having a vertically extended flange along one side that constitutes a shoe for fitting 85 against one face of the webs of the rail members, a vertically extended flange along the opposite side of the chair which is spaced apart from the rails, a filler that engages the faces of the rail webs opposite the shoe 90 engaging faces of the said rail webs, a wedge adapted for being driven downwardly between the filler and the adjacent vertical chair flange, the said wedge adapted for being forced down to its operative position 95 by the contact with the flanges of the passing wheel, as it tends to work up from between the filler and the chair flange.

4. A combined rail chair and joint comprising in combination with the adjacent ends of two rail sections; a chair including 100 a rail tie engaging base having a seat for receiving and embracing the base flanges of the adjacent rail ends, the said chair having a vertically extended flange along one side that constitutes a shoe for fitting 105 against one face of the webs of the rail members, a vertically extended flange along the opposite side of the chair which is spaced apart from the rails, a filler that engages the faces of the rail webs opposite the shoe 110 engaging faces of the said rail webs, a wedge adapted for being driven downwardly between the filler and the adjacent vertical chair flange, the said wedge adapted for being forced down to its operative position 115 by the contact with the flanges of the passing wheel as it tends to work up from between the filler and the chair flange, and means for securing the parts constituting 120 the chair and the wedge elements in transverse relation when assembled.

CHARLES MALITCH.
